UNITED STATES PATENT OFFICE.

GUSTAVUS S. LORING, OF WATERTOWN, MASSACHUSETTS, ASSIGNOR OF FIFTY-ONE ONE-HUNDREDTHS TO KIMBALL A. LORING, OF READING, MASSACHUSETTS.

ELEVATOR-OPERATING MECHANISM FOR LINOTYPE-MACHINES.

1,331,655.

Specification of Letters Patent.

Patented Feb. 24, 1920.

Application filed November 14, 1919. Serial No. 338,048.

To all whom it may concern:

Be it known that I, GUSTAVUS S. LORING, a citizen of the United States, residing at Watertown, in the county of Middlesex and 5 State of Massachusetts, have invented new and useful Improvements in Elevator-Operating Mechanism for Linotype-Machines, of which the following is a specification.

This invention relates to means for raising and lowering the elevator which constitutes an element of a linotype machine, and receives a line of matrices from the usual keyboard-controlled mechanism, and raises the line to position for transference to the 15 usual line-delivery-carriage.

The object of the invention is to provide improved means whereby the operator, by depressing a manually movable member or key lever, is enabled to connect the elevator 20 with a power-driven member of the machine in such manner that the power will raise the elevator.

The invention is embodied in the improvements which I will now proceed to describe 25 and claim.

Of the accompanying drawings forming a part of this specification—

Figure 1 is a front elevation of that portion of a linotype machine which includes 30 the elevator and mechanism embodying the invention for raising the same, the elevator being in its lowest position.

Fig. 1^a is a view similar to a portion of Fig. 1, showing certain parts in different positions.

Fig. 2 is a section on line 2—2 of Fig. 1, and a plan view of parts below said line.

Fig. 3 is a fragmentary sectional view on line 3—3 of Fig. 4.

Fig. 4 is a section on line 4—4 of Fig. 1, and an elevation of parts at the right of said line.

Fig. 5 is a fragmentary view, showing, in side elevation, the carrier hereinafter described, in its inoperative position.

Fig. 6 is a view similar to a portion of Fig. 5, showing the carrier in its operative position, and the push bar partly raised.

Fig. 7 is a view similar to a portion of Fig. 6, showing the push bar additionally raised.

Fig. 8 is a fragmentary view similar to a portion of Fig. 5, showing a modification.

The same reference characters indicate the 55 same parts in all of the figures.

The elevator the general construction of which is well known, is designated as a whole by the reference numeral 12, the elevator being movable, as usual, in fixed vertical guides, 13 and 14, and adapted, as usual, to receive a line of matrices from the inclined guide or chute 15, and to elevate the line to position for transference by the usual assembler slide, to the usual line delivery carriage, said carriage being reciprocated by the usual oscillatory carriage arm 18 attached at one end to a rock-shaft 19, which is rocked by the power of the machine.

21 represents one of the usual power-driven shafts of the machine, this being, for example, the shaft of the usual rubber roll forming a part of the automatic mechanism controlled by the keyboard for delivering matrices to the elevator. The parts above described involve nothing new, with me, excepting that the shaft 21 is utilized to rotate a driving gear 22, constituting an element of my improved mechanism, and attached to one end of said shaft.

The gear 22 constitutes the driving member of a clutch, the driven member of which is a shiftable gear 23, adapted to mesh with the gear 22, as shown by Fig. 6.

I have provided driven-member-shifting means for engaging the driven member with the driving member, at the will of the operator, the driven member being rotated by the driving member, and connections between the driven member and the elevator organized to raise the elevator when said members are interengaged, the said shifting means being embodied in the elements next described.

The carrier 24 is normally held by its own weight and that of the elevator, in the inclined inoperative position shown by Fig. 5, the center of gravity of the carrier being at the left of the center of oscillation 25. Mounted to oscillate on a stud 26 fixed to the carrier 24, is a sleeve 27 having an outer arm 28 carrying a trundle roll 29, and an inner arm 30, to the outer end of which is secured one end of a spring 31. The sleeve 27 and arms 28 and 30 constitute, in effect, a bell-crank lever. The opposite end of said spring is fixed to the carrier 24. Said arms project at different angles from the sleeve 27, as shown by Figs. 1 and 1^a, and the trundle roll 29 on the arm 28 is in the path in which the carriage arm 18 oscillates. The 110

arrangement is such that when the carriage arm 18 is at the extreme of its movement shown by Fig. 1, it bears on the roll 29 and holds the arms 28 and 29 in the positions 5 shown by Fig. 1, the arm 30 being raised and putting the spring 31 under such tension that it tends to swing the carrier 24 to the operative position shown by Figs. 6 and 7, and thus engage the driven gear 23 with 10 the driving gear 22. In other words, the spring is set for action by the carriage lever. Action of the spring to cause this swinging movement is not permitted, however, until the operator depresses a trip lever 32 by 15 means of a key 33 on the outer end of said lever. The inner end of said trip lever 32 is mounted to swing on a stud 34 fixed to the frame of the machine, and passing through a slot 36 in the carrier 24. A shoulder 35 20 on the trip lever is normally held by a spring 37, in engagement with a lug 38 on the carrier 24. When the spring 31 is tensioned or set for action by the carriage arm, as above described, and the key lever 32 is depressed by the operator, the carrier is released, and the spring swings the carrier to its operative position, and thus engages the driven gear 23 with the driving gear 22, so that the driven gear is rotated and caused 25 30 to raise the elevator 12 through the connections next described.

40 represents a push bar, which is slidable on the carrier 24, and is movable endwise by the driven gear through suitable connections 35 therewith, one end of said bar bearing on an abutment on the elevator. The push bar as here shown, is provided with rack teeth 41 meshing with a gear 42, which is fixed to the shaft 27. The shaft 27, the gear 42, and 40 the rack teeth constitute connections between the driven member 23 and the push bar which operate when the driving and driven members are interengaged, to raise the push bar and cause it to raise the elevator. The 45 abutment on the elevator with which the push bar coöperates, is preferably constructed to form a cushioning buffer which arrests the elevator without jar at the upper end of its movement. Said abutment is preferably embodied in a rod 45 (Fig. 3), movable in a socket 46 in an arm 47 on the elevator, and provided at its upper end with a stop nut 48, and at its opposite end with a head 49, having ears in which an antifriction roll 50 is journaled, and a spring 51 (Fig. 3), interposed between the head and a shoulder at one end of the socket 46. The roll 50 contacts with the upper end of the push bar when the latter is raised, and is in 50 55 rolling contact with the push bar to compensate for the swinging movements of the carrier and push bar.

The driving and driven gears remain in engagement so long as the carriage lever 18 65 remains in the position shown by Fig. 1.

When said lever moves from said position, as shown by Fig. 1^a, the spring 31 contracts until its tension is no longer sufficient to hold the gears interengaged, whereupon the carrier 24 swings back to the inoperative 70 position shown by Fig. 5, and separates the gear 23 from the driving gear, so that the push bar and elevator are free to drop. This movement of the carrier permits the key lever shoulder 35 to again engage the lug 75 38, and thus lock the carrier in its inoperative position, and enable the spring 31 to be again set for action by the carriage lever 18. The spring 31 in contracting depresses the arm 30 and raises the arm 28 to position to 80 be again acted on by the carriage lever.

It will be seen that the machine, as above described, includes carrier-shifting mechanism embodied in the manually movable lever 32, and means coöperating therewith to shift 85 the carrier to its operative position when said lever is manually moved, said coöperating means including the carriage arm 18, the shifting spring 31, and the bell-crank lever in the path of the carriage arm and 90 connected with the shifting spring, the lever 36 being adapted to lock the carrier in its inoperative position while the spring is being set for action, and to release the carrier and permit the spring to act.

95

Fig. 8 shows a differently organized carrier-shifting mechanism, embodied in a manually movable lever 32^a, pivoted at 34^a to a fixed support 26^a to which the carrier 24 is pivoted at 25^a. The lever 32^a is provided 100 with a short arm 55 projecting from the opposite side of the pivot 34^a, and bearing on a pin or abutment 56 fixed to the carrier 24. A spring 57 secured at one end to the carrier and at the other end to the machine frame, 105 normally holds the carrier in its inoperative position, the arrangement being such that the carrier is shifted to its operative position, and held in said position by the muscular force of the operator exerted on 110 the lever 32^a, until the elevator reaches its highest point.

While the coöperating means shown by Figs. 1 to 7, is preferred by me because the operator is required only to exert on the 115 lever 32 the force required to unlock the carrier, and is not obliged to hold the lever while the elevator is rising, I elect to claim broadly in this application carrier-shifting means including a manually movable lever 120 and means coöperating therewith, to shift the carrier to its operative position when the lever is manually moved, whether the said coöperating means be embodied as shown by Figs. 1 to 7, or otherwise embodied, as 125 shown for example by Fig. 8.

The elevator is arrested in its raised position by the means usually employed for that purpose in linotype machines. In the very brief period between the arrest of the ele- 130

vator and the movement of the carriage arm 18, which causes the separation of the driven gear 23 from the driving gear 22, in the preferred embodiment of the invention, the rotation of the driving gear shaft 21 stops momentarily, owing to the fact that said shaft is driven by a belt, not shown, running on a pulley on the shaft and adapted to slip on the pulley. The said belt also slips on the pulley when the invention is embodied as indicated by Fig. 8, and when the operator holds the lever 32^a depressed after the arrest of the elevator in its raised position.

I claim:

1. A linotype machine comprising a line elevator provided with an abutment, a driving gear fixed to one of the shafts of the machine, a shiftable carrier oscillatable on a fixed center, a driven gear journaled in said carrier and engageable with the driving gear by a movement of the carrier, the carrier being normally in an inoperative position, a push bar slideable on the carrier, and bearing on said abutment, and connections between the push bar and the driven gear, whereby the push bar is moved endwise when the said driving and driven gears are interengaged, carrier-shifting mechanism being provided, including a manually movable lever, and means coöperating therewith to shift the carrier to its operative position when the lever is manually moved.

2. A linotype machine comprising a line elevator provided with an abutment, a driving gear fixed to one of the shafts of the machine, a shiftable carrier oscillatable on a fixed center, a driven gear journaled in said carrier and engageable with the driving gear by a movement of the carrier, the carrier being normally in an inoperative position, a lifting gear fixed to the driven gear and coaxial therewith, and a push bar slideable on the carrier and bearing on said abutment, said push bar being provided with rack teeth meshing with the lifting gear, whereby the push bar is moved endwise when the said driving and driven gears are interengaged, carrier-shifting mechanism being provided, including a manually movable lever, and means coöperating therewith to shift the carrier to its operative position when the lever is manually moved.

3. A linotype machine comprising a line elevator provided with an abutment, a driving gear fixed to one of the shafts of the machine, a shiftable carrier oscillatable on a fixed center, a driven gear journaled in said carrier and engageable with the driving gear by a movement of the carrier, the carrier being normally in an inoperative position, a push bar slideable on the carrier, and bearing on said abutment, and connections between the push bar and the driven gear, whereby the push bar is moved endwise when the said driving and driven gears

are interengaged, carrier-shifting mechanism being provided, including a manually movable lever, and means coöperating therewith to shift the carrier to its operative position when the lever is manually moved, the said abutment being yieldingly connected with the elevator and constituting an elevator-cushioning buffer.

4. A linotype machine comprising a line elevator provided with an abutment, a driving gear fixed to one of the shafts of the machine, a shiftable carrier oscillatable on a fixed center, a driven gear journaled in said carrier and engageable with the driving gear by a movement of the carrier, the carrier being normally in an inoperative position, a push bar slideable on the carrier, and bearing on said abutment, and connections between the push bar and the driven gear, whereby the push bar is moved endwise when the said driving and driven gears are interengaged, carrier-shifting mechanism being provided, including a manually movable lever, and means coöperating therewith to shift the carrier to its operative position when the lever is manually moved, the said abutment being provided with an antifriction roll in rolling contact with the push bar.

5. A linotype machine comprising, in addition to an oscillating carriage arm, and a line elevator having an abutment, a driving gear fixed to one of the shafts of the machine, a shiftable carrier oscillatable on a fixed center, a driven gear journaled in said carrier and engageable with the driving gear by a movement of the carrier, the carrier being normally in an inoperative position, a push bar slideable on the carriage and bearing on said abutment, connections between the push bar and the driven gear whereby the push bar is moved endwise when the said driving and driven gears are interengaged, carrier-shifting mechanism being provided including a manually movable lever, adapted to lock the carrier in its inoperative position, the said carriage arm, a carrier-shifting spring, and means operable by a movement of the carriage arm to set said spring for action when the carrier is locked, said lever being manually movable to unlock the carrier and permit said spring to act.

6. A linotype machine comprising, in addition to an oscillating carriage arm, and a line elevator having an abutment, a driving gear fixed to one of the shafts of the machine, a shiftable carrier oscillatable on a fixed center, a driven gear journaled in said carrier and engageable with said driving gear by a movement of the carrier, the carrier being normally in an inoperative position, a push bar slideable on the carrier, and bearing on said abutment, connections between the push bar and the driven gear, whereby the push bar is moved endwise

when the said gears are interengaged, a normally inoperative shifting spring connected with the carrier, means actuated by a movement of the carriage lever in one direction for setting the shifting spring to render it operative, the spring being rendered inoperative by an opposite movement of the carriage arm, and means for automatically locking the carrier in its inoperative position to permit the setting of said spring by the carriage arm, said means including a manually movable lever, whereby the carrier may be released to permit the action of the shifting spring.

7. A linotype machine comprising, in addition to an oscillating carriage arm, and a line elevator having an abutment, a driving gear fixed to one of the shafts of the machine, a shiftable carrier oscillatable on a fixed center, a driven gear journaled in said carrier and engageable with said driving gear by a movement of the carrier, the carrier being normally in an inoperative position, a push bar slideable on the carrier, and bearing on said abutment, connections between the push bar and the driven gear, whereby the push bar is moved endwise when the said gears are interengaged, a normally inoperative shifting spring connected with the carrier, a bell-crank lever mounted to oscillate on a fixed support, one arm of said lever being in the path of the carriage arm, and the other being connected with said spring, the arrangement being such that a movement of the carriage arm in one direction turns the bell-crank lever to set the spring for action, while a movement of the carriage arm in the opposite direction renders the spring inoperative, and means

for automatically locking the carrier in its 40 inoperative position to permit the setting of said spring by the carriage arm, said means including a manually movable lever, whereby the carrier may be released to permit the action of the shifting spring. 45

8. A linotype machine comprising, in addition to an oscillating carriage arm, and a line elevator having an abutment, a driving gear fixed to one of the shafts of the machine, a shiftable carrier oscillatable on a 50 fixed center, a driven gear journaled in said carrier and engageable with said driving gear by a movement of the carrier, the carrier being normally in an inoperative position, a push bar slideable on the carrier, and 55 bearing on said abutment, connections between the push bar and the driven gear, whereby the push bar is moved endwise when the said gears are interengaged, a normally inoperative shifting spring connected with 60 the carrier, means actuated by the movement of the carrier lever in one direction for setting the shifting spring to render it operative, the spring being rendered inoperative by an opposite movement of the carriage 65 arm, the carrier being provided with a locking lug, and a manually movable trip lever pivoted to a fixed support and provided with a lug-engaging shoulder, said trip-lever being yieldingly held in position to engage 70 said lug and lock the carrier in its inoperative position, to permit the setting of the shifting spring by the carriage arm, and displaceable from said position to permit the action of the shifting spring. 75

In testimony whereof I have affixed my signature.

GUSTAVUS S. LORING.
